P. H. Wolfaardt. INVENTOR.

BY

E. O. Vrooman & Co., his ATTORNEY'S.

UNITED STATES PATENT OFFICE.

PIETER HENDRIK WOLFAARDT, OF BLOEMHOF, TRANSVAAL, SOUTH AFRICA.

ELECTRICAL SWITCH FOR MECHANICAL SIGNALS.

1,413,249.

Specification of Letters Patent. Patented Apr. 18, 1922.

Original application filed April 27, 1920, Serial No. 286,056. Divided and this application filed November 11, 1920, Serial No. 423,404. Renewed February 28, 1922. Serial No. 539,911.

To all whom it may concern:

Be it known that I, PIETER H. WOLFAARDT, a subject of the King of England, residing at Bloemhof, Transvaal, South Africa, have 5 invented certain new and useful Improvements in Electrical Switches for Mechanical Signals, of which the following is a specification, reference being had therein to the accompanying drawings.

10 This invention relates to an electrical switch for a mechanical signal, and this application is a divisional case from the original application, Serial No. 286,056, upon which United States Patent No. 1,338,114 15 issued April 27, 1920, and entitled "Signal for motor vehicles."

The object of the invention is the construction of a simple and efficient switch device for closing a circuit at pre-determined 20 times in a mechanical signal apparatus.

With this and other objects in view, my invention comprises certain novel combinations, constructions and arrangements of parts as will be hereinafter described, illustrated in the accompanying drawings, and more particularly pointed out in the appended claims.

In the drawings:

Figure 1 is a vertical sectional view of a 30 device constructed in accordance with the present invention.

Figure 2 is a bottom plan view of the arm-carrying head, showing the primary contact ring and the auxiliary contact plates attached thereto.

Figure 3 is a vertical sectional view of one of the contact devices.

As explained in my United States Patent No. 1,338,114, the casing 1 is provided, in 40 which is a vertical shaft 2, to the upper end of which shaft is attached the arm-carrying head 3. On a suitable support 4, in the casing 1, are the primary contact device 5 and the auxiliary contact device 6; these contact 45 devices are duplicates in structure, and will be, hereinafter, specifically described.

The arm-carrying head is provided with a plurality of angle plates 7, fastened to the side and bottom of the head 3 by screws 50 8; these angle plates 7 constitute auxiliary contacts; it is to be understood that the head 3 is formed of non-conducting material, so that if the auxiliary contact device 6 is bearing against a portion of the head 3, be-

tween two contiguous auxiliary contacts, or 55 plates 7, the circuit will be open.

The primary contact plate or ring 9 is fastened, by screws 10, in horizontal bifurcated portions 11 of the angle plates or auxiliary contacts.

Each contact device (Fig. 3) comprises a body 12, resting upon the support 4, and the body has an aperture 13, through which a screw or other ordinary device may extend into the support 4, for holding the body upon 65 the support. A vertical pocket 14 is formed in the body 12, at its outer end, and the lower end of the pocket is closed by a threaded member 15. A casing 16, having a closed, 70 upper, rounded end is slidably mounted in the upper end of the pocket 14, and a coil spring 17 is positioned in the casing and presses, at its lower end, against the threaded member 15, whereby the rounded, upper end of casing 16 is held in engagement, at all 75 times, with the ring 9, in the case of the primary contact device, and in the case of the auxiliary contact device, the upper end of the casing 16 is held either against the bottom face of the head 3, or the angle plates, 80 or auxiliary contacts.

Wires 18 are placed, at their inner ends, into the bodies 12 (Fig. 3) and set-screws 19 retain these wires (leading to signals, alarms, or indicators) securely fastened to the 85 bodies 12.

It will be understood that the circuit is completed through the primary and auxiliary contact devices, ring 9 and auxiliary contact 90 7; when the casing 16, of the auxiliary contact device 6, is pressing directly against the head 3, the circuit will be broken, but as soon as the casing 16 engages one of the contact devices 7, then the circuit will be complete through the contact device, the 95 ring 9 and the contact devices, to which are connected wires 18, leading to a signal of any desired type.

While I have described the preferred embodiment of my invention, and have illustrated the same in the accompanying drawings, certain minor changes or alterations may appear to one skilled in the art to which this invention relates, during the extensive manufacture of the same and I, therefore, 100 reserve the right to make such alterations or changes as shall fairly fall within the scope of the appended claims.

What I claim is:

1. In a device of the class described, the combination with a casing, of a support in said casing, a shaft in said casing, a head carried by said shaft, a primary and an auxiliary contact device carried by said support, said head being formed of insulating material and provided with a ring contacting at all times with the primary contact device, and auxiliary contacting means on said head and contacting with the auxiliary contact device for closing a circuit through the contact devices, ring and the auxiliary contacting means.
- 15 2. In a device of the class described, the combination with a casing, of a support resting upon the bottom of said casing, a vertical shaft in said casing, an arm-carrying

head secured to the shaft near its upper end, angle contact plates secured to the side and bottom of said head, said plates constituting auxiliary contacts, each plate provided with a horizontal, bifurcated portion, a plate or ring in the bifurcated portions of all of said plates, means fastening said ring in said bifurcated portions, a primary and an auxiliary contact device carried by said support, and said primary device contacting with said ring at all times and the auxiliary contact device adapted to alternately contact with the auxiliary contacts for closing a circuit through the auxiliary contacts, ring and contact devices.

In testimony whereof I hereunto affix my signature.

PIETER HENDRIK WOLFAARDT.
